MACHINE FOR FINISHING GEARS

Ernest A. Overstedt, Detroit, Mich., assignor, by
mesne assignments, to Michigan Tool Company,
Detroit, Mich., a corporation of Delaware

Application December 6, 1933, Serial No. 701,097

11 Claims. (Cl. 90—1.6)

My invention relates to machines and particularly to a machine for accurately finishing roughed out gear teeth to accurate form.

Heretofore a grinding operation was usually utilized for finishing gears to accurate dimensions which was slow and costly. Burnishing and lapping machines were also employed in an attempt to produce accurate tooth forms. While lapping, grinding and burnishing were utilized with success on certain types of gears, none of these operations solved the problem of accurately finishing gears in an exceeding rapid manner as accomplished by the present machine.

The machine utilizes the rack type principle for generating true involute forms on the teeth of gears in an exceedingly rapid manner. A tool is constructed of a plurality of blades upon the top edges of which teeth are provided having flat sloping surfaces which are grooved to provide closely adjacent cutting edges. The cutting edges are disposed vertical of the tool, normal to the length of the tooth, to eliminate any machining due to the roll of the gear when the gear and tool are operated in synchronism with each other. Various methods may be utilized for providing a lateral movement between the gear and tool when operated in meshed relation, such as providing a lateral movement to the tool or to the gear, but I prefer to offset the axis of the gear to the plane of operation of the tool so as to produce a lateral slippage between the teeth of the tool and those of the gear while they are relatively operated. This is effected by mating a spiral gear with a spur tool or a spur gear with a spiral tool or when the angle between the plane of operation of the gear and tool is to be less than the spiral lead of the gear teeth then the spur gear may be mounted on a spur tool of shorter lead.

The present machine embodies the movement of the tool in reciprocation to rotate the gear during the time the gear is fed downwardly onto the tool under a predetermined pressure. The machine may be set to have the tool reciprocate a predetermined number of times or may be set to have the tool reciprocate until the gear has been machined to a desired diameter, after which the machine ceases to operate. During the machining operation the gear is preferably fed laterally across the tool to produce even wear on the tool teeth. The control illustrated is hydraulic, the fluid, which is preferably oil, is pumped by suitable mechanism into a cylinder to reciprocate the tool and into various other cylinders to effect the complete operation of the

5 machine which will be later described. An electric motor is preferably employed for driving a pump associated with the hydraulic mechanism but it is to be understood that the various movements of the machine elements could be obtained by mechanical rather than hydraulic means.

Accordingly, the main objects of my invention are, to construct a machine having a bed whereon a cutting tool may be reciprocated; to provide a head for the machine in which a gear 10 to be machined may be mounted and which is constructed to be adjustable to have the lead of the teeth of the gears mesh with the teeth of the rack so that their planes of operation will be intersecting; to feed the gear into the tool with a predetermined pressure; to feed the gear and tool laterally, relative to each other, to produce uniform wear on the tool teeth; to provide a control mechanism for the machine which may 15 permit the tool to reciprocate a predetermined number of times or which may feed the gear into the tool until a desired gear diameter is reached, after which the machine is stopped; and, in general, to provide a machine for accurately 20 finishing gears which is simple in operation, rigid in construction and economical of manufacture.

Other objects and features of novelty of my invention will be either specifically pointed out 25 or will become apparent when referring, for a better understanding of my invention, to the following description taken in conjunction with the accompanying drawings, wherein:

Fig. 20 is a plan view of a cam shown in the structure illustrated in Fig. 16.

Fig. 21 is a plan view of a cam which mates with the cam illustrated in Fig. 20, and

Fig. 22 is a broken diagrammatic view of the circulating system to be employed with the head actuating device illustrated in Figs. 15 and 16.

In the drawings, I have illustrated a machine for actuating a tool in reciprocation for rotating a gear to be accurately finished. The tool is of the rack type, fabricated from a plurality of like blades which are accurately constructed, having teeth on the ends thereof, the sides of which are plane surfaces disposed in predetermined angular relation and provided with a plurality of juxtaposed grooves, providing lands having cutting edges on each side which are capable of machining in opposite directions. The plane of operation of the tool and the gear to be machined are angularly disposed when the teeth of the gear are mated with those of the tool, to effect a lateral slippage between the mated teeth sides during the time the gear and tool are relatively actuated.

In view of the vertical disposition of the cutting edges on the sides of the teeth of the cutting tool, no cutting is effected due to the roll of the gear in synchronism with the tool and cutting is only produced in the presence of a lateral slippage between the teeth. The method of operation between the teeth of the cutting tool and the gear, to produce an accurate generation of the gear teeth flanks, has been clearly set forth, described and claimed in the copending application of William F. Dalzen, Serial Number 554,193, filed July 31, 1931, and assigned to the assignee of the present invention.

The machine disclosed in Figs. 1, 2, 4 and 14 is of the hydraulically actuated type, and while reference will be had only to this type of operating mechanism, it is to be understood that the same results may be obtained mechanically, electrically or by other well known operating means, or a combination thereof. Hydraulic mechanism is disposed in the base of the machine and em-

ployed to actuate the tool in reciprocation and to effect the feeding of the head, supporting the gear to be machined, toward the tool under suitable and predetermined pressure. Control mechanism is provided for effecting the reciprocation a predetermined number of times, which may be varied at the will of the operator, to regulate the number of cycles of operation of the tool on a gear, after which the machine automatically ceases operation. Suitable means is provided for feeding the head laterally of the tool to advance the gear thereacross to produce even wear on the tool teeth. As a further modified form of the device, a second head is illustrated which may be employed for controlling the feeding of the gear into the rack so as to have the machine continue to operate until a desired gear diameter is produced.

A T-shaped base 25, has a front portion 26 which encloses an oil gear mechanism 39 and embodies ways 27 upon which a tool carrying table 28 is reciprocated. A central rearwardly extending portion 29 supports a pillar 31 upon which a gear supporting head 32 is adjustably secured. The pillar 31 is adjustable forwardly and rearwardly upon the base portion 29 and is clamped in fixed adjusted position by a plurality of bolts 33. A slide 34 is carried on the front face of the pillar 31 to adjustably support the head 32 a set distance above the table 28. The hand wheel 35 operates a lead screw (not shown) by which the slide 34 is adjusted after which it may be clamped in fixed relation to the pillar 31 by a plurality of bolts 36. In this manner, through the forward and rearward movement of the pillar 31 and the vertical adjustment of the slide 34, the head 32 is positioned over the tool carrying table 28.

The table 28 has a tool 37 bolted or otherwise secured thereto to reciprocate therewith. The tool 37 is in the nature of a rack made up of a plurality of like blades 38 upon the faces of which a plurality of closely adjacent cutting edges are disposed. As pointed out hereinabove, the blades and the method of use is described and claimed in the above mentioned copending application and will not be described in detail herein.

The hydraulic mechanism 39, illustrated in Fig. 12, and disposed in the base portion 26 of the machine, is driven preferably by an electric motor 41 attached to or disposed adjacent to the base of the machine. Two independent but unit constructed cylinders 42 and 43 are secured to the underside of the table 28 to be supported and carried thereby on the ways 27. Conduits 44 and 45 are sealed into the ends of the cylinders 42 and 43 respectively, which are disposed in opposite directions and which produce the reciprocation of the table 28 through the introduction of pressure into the conduit 44 alternately with the introduction of pressure into the conduit 45. Suitable valve means and control therefor for regulating the alternate introduction of pressure between the conduits will be described more fully hereinafter.

The head 32 carries a gear supporting frame 46 which is angularly adjusted relative to the head by the actuating of a clamping device 47. By means of this adjustment, the gear to be machined has its axis of rotation adjusted to the proper degree of angularity with the plane of movement of the tool 38 to have the teeth of the gear and those of the tool accurately mated. It will be understood that for obtaining such relation, a spur type of gear would be mounted on a

spiral tool and a spiral type of gear would be mounted on a spur tool, or a spiral tool of shorter lead. In any case the mounting should be such that a proper degree of angularity is present between the plane of rotation of the gear and the plane of operation of the tool. This degree of angularity should preferably be less than 30° . An angularity between 3° to 20° has produced very satisfactory results. Once however the tool is constructed for a particular gear, the angularity becomes a fixed quantity so as to have the teeth of the gear accurately mate with the teeth of the tool.

Referring to Fig. 1, a gear 48 is clamped to a shaft 49 which is disposed between a fixed center 51 and a longitudinally movable center 52 for rotation. The pivot 52 is adjusted forwardly and backwardly relative to the shaft 49 by a hand wheel 53 to permit the gear to be removed and a gear to be machined installed, after which the movable center 52 is retained in locked position by a clamping screw operated by a hand wheel 54.

During the relative movement of the gear 48 and the cutting tool 38, oil is freely pumped onto the tool through the conduit 55. The oil washes out the chips between the teeth of the cutting tool, lubricates the lands of the teeth of the tool to eliminate any friction and a burnishing operation from being produced thereby, and prevents any heat being generated in the tool.

The oil flows over the tool 38 into the table 28 into pockets 56 thereof, as clearly disclosed in Fig. 5. A considerable amount of the chips produced during the machining operation are retained by the pockets 56 and the oil is conducted therefrom through a spout 57 into a trough 58 disposed on the back side of the base portion 26 of the machine as illustrated in Figs. 4 and 5. A pipe 59 extends from the trough 58 into a sloping receptacle 61 to have any of the chips carried therethrough deposited in the bottom of the base 26 of the machine. A screen 62 is disposed parallel to the sloping wall to the receptacle 61 and prevents the chips from passing to the front part of the machine, as illustrated clearly in Fig. 5. A suitable cover 63 is provided for enclosing the receptacle 61 and the pipe 59, which provides an entrance to the base of the machine for the removal of the chips.

A pipe 64 extends into the front side of the oil reservoir where strained or filtered oil will be present to be pumped through the conduit 55 over the tool 38, as above described. While I specify that the element 62 is a screen, it will be understood that a suitable filter element could be employed when found necessary. The ways 21 upon which the table 28 reciprocates are preferably provided with a plurality of rollers (not shown) upon which the table 28 contacts through the projecting angular shaped portions 65, to roll thereon.

Referring to Fig. 1, a suitable control mechanism 66 is disposed on the front side of the base 26 having a handle 67 thereon by which the operation of the machine is controlled. The mechanism may be set to produce a predetermined number of reciprocations to the tables 28 after which the table is automatically stopped. It is only necessary for the operator once the mechanism is adjusted to move the handle through a small arc to have the machine commence operation, after the completion of which the machine will automatically stop. A handle 68 is provided on the oil gear mechanism 39 by which the speed of operation of the tool in reciprocation is con-

trolled. A locking handle 69 retains the handle 68 in adjusted position.

The mechanism 66 illustrated enlarged in Figs. 6, 7 and 8, comprises a housing 71 having a cover 52 therefor through which a shaft 73 projects, supported on a bearing bracket 74. The shaft 73 is keyed to an arm 75 which operates a pull rod 76 illustrated in Figs. 8 and 12. The purpose of the mechanism is to move the rod 76 outwardly from the drawing through the counter-clockwise movement of the arm 75 and to lock the arm in moved position for a predetermined number of strokes of the machine. The movement of the rod 76 causes the table 28 to be actuated in a manner which will be described hereinafter. The table will continue to operate until the rod 76 is released through the clock-wise movement of the arm 75 which is controlled by the adjustment mechanism 66.

Upon the shaft 73 a collar 77 is mounted by a key 78 and screw 79 in fixed relation thereto. An extending arm 81 is provided on the collar 77 on the upper end of which a pivoted tripping and locking detent 82 is mounted. The extending arm 83 on the detent 82 functions as a latch for engaging a hardened plate 84 on a cast boss 85 provided on the housing 71. When the latch 83 engages the hardened plate 84, the arm 81 retains the shaft 73 and arm 75 in counter-clockwise rotated position to retain the shaft 76 in moved position.

Bearing surfaces 86 are provided on the inner face of the collar 77 upon which two ratchet wheels 87 and 88 are rotatably mounted. The ratchet wheels have teeth 89 thereon which are disposed in the opposite direction and are retained in fixed relation to each other by rivets 91. A suitable spring 92 engages the teeth of the ratchet wheel 88 for preventing the counter-clockwise rotation of the ratchet wheels. Frontwardly of the bearing surface 86 on the collar 77 an extension 93 is provided by which the collar and shaft are moved to latch position.

On the front end of the shaft 73, I have mounted a second collar 94 which is rotatable on the shaft and which has an extension 95 which advances toward and engages the extension 93 to rotate the collar 77 and the arm 75 in counter-clockwise direction to a position to permit the latch 83 to engage the hardened plate 84 of the cast boss 85.

Upon the collar 94 is mounted a collar 96 for rotational movement, having thereon a projecting arm 97 upon which a ratchet finger 98 is mounted to mate with the teeth of the ratchet wheel 87, biased into engagement with the teeth thereof by a spring 99. The handle 67 is provided with an inwardly projecting lug 101 which engages the portion 102 of the finger 98 to compress the spring 99 and raise the finger 98 out of engagement with the teeth 88 of the ratchet wheel 87. The handle advances the ratchet finger 98 and the arm 97 as it is moved counter-clockwise until the extension 95 on the collar 94 engages the extension 93 on the collar 77 to move the rod 76 to starting position. The handle is then returned to initial position.

A housing 103 extends upwardly from the housing 71, being a part thereof, and has therein a slide 104 which is provided on its lower end with a pivoted finger 105 which engages the teeth 89 of the ratchet wheel 88 for turning the ratchet wheels clockwise a predetermined amount with each downward movement of the slide 104. A spring 106 is disposed within the slide to re-

turn it to its initial position. The upper end of the slide extends inwardly, at 107, and is provided with a roller 108 which is contacted by a cam (not shown) on the side of the machine for moving the slide downwardly once during a complete cycle of movement, that is to say, a forward and back movement of the table 28.

The clockwise movement of the ratchet wheels 87 and 88 causes the arm 97 and the ratchet finger 98 to be revolved in a clockwise direction a predetermined angular amount for each reciprocation of the slide. The end 102 of the ratchet finger 98 strikes an extending lug 109 of the detent 82 and raises the latching finger 83 from contact with the hardened plate 84 to effect the release of the arm 81, shaft 73, arm 75 and rod 76 to permit the reverse movement of the rod 76 to shut down the machine.

By positioning the handle 67 relative to the collar 94 through the adjustment of screws 111, the extension 101 on the handle is adjusted relative to the extension 95 which thereby regulates the position of the finger 98 relative to the lug 109, to control the amount of clockwise movement of the ratchet wheels 87 and 88 required to have the end 102 of the cam finger 98 strike the lug 109 to stop the machine. In this manner any number of strokes can be produced to the table 28 before the table is stopped and the machining operation completed.

Referring to Figs. 9, 10 and 11, I have illustrated the head adjusting mechanism 32 which is employed to feed the gear a predetermined amount toward the tool, once during a complete cycle of movement of the table. The slide 34 has a forwardly projecting housing 112 having dovetailed ways 113 thereon which support a frame 114 for lateral movement. The frame 114 is provided with a separate bearing surface 115 to permit the frame to be assembled on the ways 113. The housing 112 has a slot 116 therein through which a boss 117 extends and which is secured to the frame 114. A conical roller 118 is carried by the boss 117 in engagement with a cam wheel 119, illustrated more clearly in Fig. 10.

The cam wheel 119 is mounted on a shaft 121 which is geared through suitable gearing to a shaft 122 mounted for rotational movement on the housing 112, as illustrated in Fig. 2. A ratchet wheel 123 is fixed to the shaft 122 and is actuated by a pawl 124 mounted on an extension 125 of a swinging arm 126. The arm is provided with an extensible finger 127 which may be adjusted on the arm 126 relative to the position of the gear carrying element 46 on the table 28. An adjusting screw 128 is mounted on the arm 126 to control the clockwise swinging movement of the arm.

An adjustable boss (not shown) is carried by the rear side of the table 28 for engagement with the finger 127 to move the arm 126 in counter-clockwise direction for advancing the ratchet wheel 123 one or more teeth during each cycle of reciprocation of the table. In this manner the cam wheel 119 is operated to very slowly move the frame 114 in oscillation laterally of the plane of movement of the rack. This movement carries the gear backwardly and forwardly across the face of the teeth of the tool for the purpose of distributing wear evenly thereover. The housing 112 has a cover 129 thereon for the opening adjacent to the cam wheel 119 which is retained by lock and handle 131.

The frame 114 is provided with a housing 132

at the top in which a support 133 for the head 32 is retained on a cam slide 134. Cam engaging bearing elements 135 are carried by the supporting element 133. The slide 134 is actuated by a piston rod 136 which is fixed thereto and which is bearinged in the frame 114 by the threaded collar 137. The piston rod 136 has a piston thereon (not shown) which is encompassed by a cylinder 138 having an inlet port 139 and an outlet port 141 communicating with the interior of the cylinder. When the fluid ahead of the piston is bled from the port 141, the cam slide 134 is moved to the right, as viewed in Fig. 9, to cause the supporting element 133 and the head 32 to be moved downwardly. When pressure is introduced into the cylinder through the port 141, the cam slide 134 is moved to the left as viewed in Fig. 9, and the supporting element 133 for the head 32 is moved to raised position, raising the gear from the tool. When a new gear is placed in the head, a pressure is introduced ahead of the piston through the port 139 to move the cam slide 134 to the right, as viewed in Fig. 9, to force the supporting element 133 and head 32 downwardly to force the gear into contact with the tool under a predetermined pressure. For effecting this feed at a constant pressure, suitable valve means is provided in communication with the outlet port 141 for bleeding the fluid on the right hand side of the piston from the cylinder to permit the movement of the cam slide 134 to the right to lower the head 32. The bleeding valve will be described more fully hereinafter.

The supporting element 133 has a head 142 of a shaft 143 supported thereon for rotational movement by a collar 144. The lower end of the shaft 143 has a shoulder bearing end 145 engaged in a shouldered aperture 146 of a threaded stud 147 which is locked to a threaded extending boss 148 of the frame 114, by a nut 149. The shouldering of the end 145 in the aperture 146 provides a stop to the downward movement of the head 32 which may be adjusted through the adjustment of the stud 147 in the boss 148.

A thread 151 is provided on the shaft 143 in engagement with a threaded nut 152 which is fixed to a boss 153 of the frame 154 in support of the head 32. A worm wheel 155 is fixed to the shaft 143 by suitable key means, to be actuated by a worm 156 to adjust the frame 154 independent of the supporting element 133, to thereby regulate the head in accordance with different gear diameters, the feed movement remaining the same. After the shaft 143 is rotated, to adjust the frame 154 to proper height, a screw 157 is actuated to force a bronze clamping element 158 against the shaft to prevent it from turning. The end of the frame 154 carries the gear supporting element 46 on a centrally disposed shaft 159.

The shaft 159 has a head 161 which is retained in fixed relation to the frame 154 by a screw 162, and after the plate 46 is disposed on the shaft a bearing 163 is retained against the plate by a screw 164. The inner peripheral edge of the outer face of the nut 164 is provided with a plurality of notches 165 in which a locking key 166 is engaged when retained in a slot on the end of the shaft 159 by screws 167.

The peripheral edge of the frame 154 is grooved to form a worm wheel 168 which is engaged by a worm 169 which is part of the adjusting device 47. The bottom portion of the plate 46 is provided with dovetail ways 171 upon which a head stock 172 carrying the center 52 and a tail stock

173 carrying the center 51 are adjustably clamped. By the adjustment of the worm 169, the plate 46 is caused to travel about the shaft 159 to adjust the head and tail stocks 172 and 173 angularly relative to the plane of movement of the table 28 for the purpose mentioned hereinabove.

The bleeding valve above referred to, is illustrated in Fig. 13 as comprising a frame 174 having a chamber 175 and a chamber 176 therein. A conduit 177 extends from a control valve 178, in the gear mechanism 39, illustrated in Fig. 12, to communicate with the chamber 175. A conduit 179 extends from the chamber 176 and is connected by a flexible tube to the port 141 of the cylinder 138. A large vent 181 connects the chambers 175 and 176 at one end while a small vent 182 connects the two chambers at the opposite ends. Valve seats are formed on the end of the vents 181 and 182 at the point of communication with the chamber 176.

A valve 183 is retained by gravity in sealed relation to the seat of the vent 181, having a downwardly projecting guide extension 184 which retains the valve in aligned relation with the vent and a projection 185 at the top to prevent the valve from sealing the opening through the conduit 179. When oil is introduced through the conduit 177, it passes through the chamber 175 through the vent 181, raises the valve 183, passes through the aperture 179, through the port 141 to the cylinder 138 to cause the piston rod 136 to be moved to the left, as viewed in Fig. 10. This actuates the cam slide 134 to the left to move the supporting element 133 and head 32 upwardly, which occurs when the cycle of operation of the machine is completed.

During the machining operation, as pointed out hereinabove, the fluid is bled from the chamber 138 from the port 141 to permit a constant pressure to be applied to the frame 154 downwardly at the time the frame 154 is fed downwardly due to the bleeding of the fluid from the port 141. This is effected through the vent 182 of the bleeding valve 174 by a valve 186 which engages the seat of the vent 182 and which is biased into a sealed position by a spring 187.

A shaft 188 extends upwardly from the sealing valve 186 and has a suitable packing head 189 disposed thereabout to prevent the passage of liquid therethrough during the reciprocation of the stem 188. A shouldered nut 191 provided on the threaded end of the stem 188 may be adjusted to regulate the amount of fluid which may pass through the vent 182 each time the valve 186 is raised. A lever 192 is pivoted at 193 and has a bifurcated end 194 which spans the nut 191 and has an extending leg 195 on its opposite end which is engaged by trip element 196. The element 196 is pivoted to effect a swinging movement when the table is moved to the left, as viewed in Fig. 13. A stop pin 197 engages the element 196 and causes the clockwise movement of the lever 192 when the table 28 moves to the right through the engagement of the element 196 with the extension 195 to cause the stem 188 to be raised. The valve 178 is so constructed as to have the conduit 177 function to exhaust any fluid which may be delivered thereto.

The frame 114 supports springs 201 which balance the weight of the head 32 supported on the studs 202 which extend through the springs and have adjusting nuts 203 and locking nuts 204 disposed on the end thereof, as illustrated in Fig. 11. Through the adjustment of the nuts, a prop-

er tension is provided in the springs to substantially balance the weight of the head 32.

When the handle 67 is moved to set the catch 83, the rod 76 of the hydraulic mechanism 39, as illustrated in Figure 12, is moved to the left causing the lever 198 to be moved in a counter-clockwise direction about a supporting shaft 199. The opposite end of the lever 198 has a projecting lug 205 disposed thereon and extending inwardly of the machine. The lug is disposed to engage one or the other of the collars 206 and 207 adjustably supported on the end of a shaft 208 extending from the valve 178. When the rod 76 is moved to the left to actuate the lever 198 the piston rod 208 is moved to the right to cause oil to be delivered to the inlet port 139 to actuate the head 32 downwardly. The counter-clockwise rotation of the lever 198 also operates a valve 209 through the connection of a piston rod 211 thereof with a pin 212 of the lever to introduce oil into the conduits 44 and 45 for operating the table 28 in reciprocation.

A lever 213 is pivoted at 214 to the bed of the machine, as illustrated in Fig. 1, and a projecting pin 215 on the end thereof is actuated by a cam 216 to rotate the lever 213 in a counter-clockwise direction. The opposite end of the lever is secured through a link 217 to an arm 218 which is mounted on a shaft 219 which actuates a valve in the oil gear mechanism 39 for controlling the flow of oil first through the conduit 44 and then through the conduit 45 to effect the reciprocation of the machine. A second cam lever 216 (not shown) is disposed in the side of the table 28 having the cam surface facing in the opposite direction to engage the projecting pin 215 for moving the lever 213 in a clockwise direction. This shuts off the flow of oil through the conduit 44 and opens the conduit 45 to the oil supply. The cams 216 may be set at any spaced distance along the side of the table 28 to control the length of its travel in reciprocation.

The motor 41 of the machine drives through a belt 221, a pulley 222 which operates a rotary pump 223 of the oil gear mechanism. The rotation of the wheel 222 also drives a pump 224 through a sprocket end chain connection 225 for propelling the oil flow through the conduit 55 on to the tool and gear during operation of the machine. A spring balancing device 226 is connected to the lever 198 for rotating the lever in a clockwise direction when the rod 176 is released from held position by the release of the detent 83 from the hardened plate 84 of the lug 85, as illustrated in Fig. 6.

The hydraulic mechanism, including the pump 223 and the valve gearing disclosed in Fig. 12, will not be described further or in detail since the mechanism itself is a patented article and embodies no part of the present invention except for its use in operating the various component parts of the machine proper. It has been pointed out hereinabove that the handle 68 controls the flow of oil through the conduits 44 and 45 and the speed of operation of the table 28, the handle 69 being employed to clamp the control handle 68 in any adjusted position.

The hydraulic mechanism is capable of delivering oil under two stages of pressure, the first from 80 to 100 pounds for operating the table 28 and from 500 to 600 pounds to the cylinder 138 which operating through the cam slide 134 is capable of producing a pressure of 6,000 pounds to the gear to force it into the tool.

For operating the machine after the various elements are adjusted, it is only necessary to oscillate the handle 67 once through an arc of movement to commence operation. The table will reciprocate a predetermined number of times, as above described, during which time a pressure is applied between the tool and gear and the gear is slowly fed into the tool. The gear is shifted slowly across the tool during the operation to provide for the even wear on the teeth of the tool. After a predetermined number of reciprocations of the tool, the machine automatically stops and the head and gear is raised. It is only necessary to remove the finished gear and place the second gear to be machined in the head after which the movement of the handle 67 again starts the feeding movement to the head and the reciprocation of the table to finish the gear.

In Figs. 15 to 22, inclusive, I have illustrated a modified form of adjusting head 34 which may be employed with the machine hereinbefore described. In this instance the head is so constructed as to feed the gear into the tool until the desired gear diameter is reached, after which the feeding operation is stopped and the machine itself may be stopped or additional strokes may be applied hereto before the machine ceases operation.

The frame 114 is substantially the same as that illustrated and described in regard to the head construction of Figs. 9, 10 and 11, with the exception of the construction of the shaft 143 and its accompanying mechanism which will now be described. A shaft 227 has a head 144 thereon which connects with the cam element 133 as described hereinabove. The shaft, however, is shortened and provided with threads 228 which are engaged by a gear 229 actuated by the worm wheel 136 for the purpose of adjusting the frame 231 on the shaft 227 in accordance with the gear diameter to be machined. The extending boss 146 of the frame 114 has a stud 232 of a cam plate 233 mounted thereon with the cam face disposed upwardly. A boss 234 provided on the frame 231 has a shaft 235 of a cam plate 236 retained therein for rotational movement, the cam plate 236 being disposed downwardly. The upper end of the shaft 235 is shouldered to receive ratchet wheels 237 and 238, the teeth of one of which are disposed medially of the tooth of the other wheel. The ratchet wheels are retained in fixed relation to each other by a key 239 and are biased for rotational movement by a spring 240. The cam plate 236 also forms a ratchet wheel by having ratchet teeth 242 thereon, as illustrated in Fig. 19. It will be noted in Figs. 17 and 18 that the ratchet teeth extend only part way around the ratchet wheels, the purpose of which will be explained hereinafter.

An oil cylinder and piston 243 is disposed on the side of the housing 132 of the frame 114, having a piston extending frontwardly thereof and which is provided with an eye 244 which is secured to a link 245. The link operates a shaft 246 in rotation to operate an arm 247 the end of which projects in a slot 248 of a plunger 249. The end of the plunger 249 carries ratchet wheel fingers 251 and 252 which are pivoted on a pin 253. The plunger carries springs 254 and 255 for the purpose of biasing the fingers 251 and 252 into engagement with the teeth of the ratchet wheels. The two ratchet fingers 251 and 252 are

employed with two ratchet wheels 237 and 238 for the purpose of obtaining a fine adjustment and at the same time having coarse teeth in the ratchet wheels so as to withstand wear.

5 By having the teeth offset immediately of each other on the two ratchet wheels, advancement of half of the arc subtended by a tooth is effected each time the plunger is reciprocated to the right, as viewed in the figures. To prevent the reverse 10 rotation of the ratchet wheels, the teeth 241 are provided on the cam plate 236 engaged by a ratchet finger 256 pivoted on the screw 257. A suitable spring 258 bias the finger 256 into engagement with the teeth 241 on the cam plate. 15 For releasing the cam fingers 251, 252 and 256, I have provided a cylinder 259 from which a piston rod 261 extends having truncated conical cam elements 262 and 263 thereon. When the oil gear mechanism is actuated to stop the machine, oil 20 flows into the cylinder 259 to actuate the piston rod 261 downwardly to have the cam elements 262 and 263 engage the projecting ends 264 and 265 respectively of the ratchet fingers 251 and 256. This downward movement causes the fingers 251 and 256 to be moved in a counter-clockwise direction out of engagement with the teeth of the ratchet wheel and cam plate, respectively, while at the same time a pin 266 carried by 25 the ratchet finger 251 engages a projection 267 on the ratchet finger 252 to cause it to be rotated counter-clockwise to disengaged position. When all the ratchet fingers are thus released, the tension of the spring 240 causes the ratchet wheels 30 237 and 238 and the cam plate 236 to be rotated in counter-clockwise direction to be returned to original position.

In Fig. 22, I have illustrated diagrammatically the oil control mechanism wherein a valve 268 is connected in the system and is reciprocated each time the table is reciprocated, or which may be operated once during a complete cycle of reciprocation of the table. The valve 268 feeds oil first in one end of the cylinder 243 and then 40 in the other for the purpose of reciprocating the piston and rod therein to oscillate the link 245. This oscillation causes the reciprocation of the plunger 249 and causes the fingers 251 and 252 to be reciprocated therewith to cause first one 45 and then the other to engage a tooth on one and then the other of the ratchet wheels, respectively, for advancing the shaft 235 and therefore the cam plate 236 in rotation.

When the machine is set to begin operation, 50 the pressure applied thereto through the piston rod 136 will force the head downward until the cam plates 233 and 236 contact with each other. Thus the feed movement is limited through the cam faces and the feed is obtained through the rotation of the shaft 235, as above described, to rotate the cam faces on each other to provide the feeding movement of the head and the gear. By adjusting the ratchet wheels 237 and 238 on the shaft 235, through suitable means not shown, the degree of downward feed may be limited and which, therefore, may be set to correspond with a desired gear diameter.

The rotation of the shaft 235 will continue until the ratchet fingers 251 and 252 feed all 55 of the teeth of the ratchet wheels 237 and 238 thereby and the smooth portion of the ratchet wheels are disposed adjacent to the ends of the fingers. In this manner the feeding movement is stopped and the machine may be immediately 60 shut down or if desired, a predetermined num-

ber of strokes may be provided to the tool before the shut down occurs.

A valve 269 is disposed to control the flow of fluid into the cylinders 138 and 259 for the purpose of retracting one piston when the piston of the other cylinder is advanced. In this manner when the pressure is applied to the head 32 to move the gear downwardly, the cam elements 262 and 263 are retrieved. When the pressure is released from the head 32 to raise the gear through the actuation of piston in the cylinder 138, the piston of the cylinder 259 is actuated to cause the downward movement of the cam elements to trip the ratchet fingers, as above described.

When the machine is operated with the head as above described in relation with Figs. 16 to 22, inclusive, an exact gear diameter is produced or at least the gear teeth are machined, in accordance with a desired gear diameter, after which no further machining is effected. The head is so constructed that it may be adjusted to various gear diameters within predetermined limits, after which the cam feeding mechanism may be adjusted to feed the head only until the predetermined gear diameter is reached, after which the feeding movement is stopped. The machine may, thereafter, be immediately stopped or continued in operation a number of strokes, as may be desired.

In any instance, through the vertical disposition of the cutting edges on the cutting tool, the operation of the tool and the rotation of the gear in planes which intersect at an angle, eliminates any cutting due to the roll of the gear and machines only due to the lateral slippage effected between the sides of the teeth of the gear and those of the cutting tool which machines uniformly from the crown to the root of the teeth.

While I have illustrated a machine in which a rack type of tool is employed, it is to be understood in the broad concept of the invention that circular tools may be utilized to effect the same result in the same manner.

An advantage, however, is provided in the rack type of tool in that the form on the sides of the teeth are plane surfaces and which thereby produce a true involute form on the gear teeth. When it is necessary to sharpen the teeth, it only requires a dressing operation of the plane surfaces to produce sharp cutting edges which again generate a true involute form. When sectors or circular gear shaped tool elements are provided, it is necessary to form on the flanks of the teeth, true or modified involute forms to produce an involute form on the gear. This must not only be accurately produced on the tool when constructed, but must be produced during each sharpening operation.

Through the use of the hydraulic mechanism, the operation of the various component parts of the machine are materially simplified and once the machine is set up in operation, no difficulty whatsoever is experienced due to the wear or adjustment of parts. In this type of machine two or more gears a minute may be finished to extremely accurate dimensions which is exceedingly faster than any other device known in the art is able to accurately finish teeth or gears.

While I have illustrated and described but two embodiments of my invention, it will be apparent to those skilled in the art that various changes, omissions, additions and substitutions may be made therein without departing from the

spirit and scope of my invention, as set forth in the accompanying claims.

I claim:

1. A machine for accurately finishing gears, including in combination, a bed, hydraulic mechanism in said bed, a motor for operating said mechanism, a reciprocable table on said bed, hydraulic means attached to said bed and table and connected to said mechanism, a rack tool on said table, a head above said rack having means for mounting a gear to be machined thereon, and means for moving said head towards said rack.
2. A machine for accurately finishing gears, including in combination, a bed, hydraulic mechanism in said bed, a motor for operating said mechanism, a reciprocable table on said bed, hydraulic means attached to said bed and table and connected to said mechanism, a rack tool on said table, a head above said rack having means for mounting a gear to be machined thereon, means for moving said head towards said rack, and means for shifting said rack and work gear laterally of each other.
3. A machine for accurately finishing gears which includes, in combination, a bed, a table reciprocable thereon, a tool on said table, a head mounted above said tool, means on said head for supporting a gear relative to said tool, means responsive to movement of said tool for moving said head downwardly on said tool, and additional means responsive to movement of said tool for shifting said tool and gear laterally of each other.
4. A machine for accurately finishing gears which includes, in combination, a bed, a table reciprocable thereon, a tool on said table, a head mounted above said tool, means on said head for supporting a gear relative to said tool, means for moving said head downwardly on said tool, and means for shifting said tool and gear laterally of each other, said downward movement and said lateral movement both being controlled by the table during its reciprocation.
5. A machine for rapidly finishing gears which includes, in combination, a tool for finishing a gear, means for driving the tool and gear one by the other through a predetermined cycle, a support for said gear adjustable at an angle to the plane of movement of the tool, means for moving said support to move said gear radially into said tool, and means for moving said tool and gear laterally of each other, said radial and lateral movements occurring in increments during said cycle of operation and in response to said gear and tool driving relation.
6. A machine for rapidly finishing gears which includes, in combination, a tool for finishing a gear, means for driving the tool and gear one by the other through a predetermined cycle, a support for said gear adjustable at an angle to the plane of movement of the tool, means for moving said support to move said gear radially into said tool, and means for moving said tool and gear laterally of each other, said radial and lateral movements occurring in increments during said cycle of operation and being controlled by the relative driving movement between said gear and tool.
7. A machine for finishing gears which includes, in combination, a rack tool, a source of power for driving said tool in reciprocation, a head movable toward said tool, a work supporting element carried by said head and rotatable relative thereto, and means actuated by said

source of power for moving said head toward said tool.

8. A machine for finishing gears which includes, in combination, a rack tool, a source of power for driving said tool in reciprocation, a head movable toward said tool, a work supporting element carried by said head and rotatable relative thereto, means actuated by said source of power for moving said head toward said tool, and additional means actuated by said source of power for feeding said work and tool laterally of each other during the driving of the tool.

9. A machine for accurately finishing the working surfaces of the teeth of roughed out gears, including in combination, a bed, a table mounted for reciprocating movement on said bed, a rack type tool mounted on said table, said tool having teeth conjugate to the teeth to be produced on a gear to be finished, a head disposed above said tool, means on said head for rotatably mounting a gear to be finished in meshing engagement with said tool and means responsive to reciprocation of said table for feeding said head downwardly toward said tool.

10. A machine for accurately finishing the working surfaces of the teeth of roughed out gears, including in combination, a bed, a table

mounted for reciprocating movement on said bed, a rack type tool mounted on said table, said tool having teeth conjugate to the teeth to be produced on a gear to be finished, a head disposed above said tool, means on said head for rotatably mounting a gear to be finished in meshing engagement with said tool, means responsive to reciprocation of said table for feeding said head downwardly toward said tool and means for shifting said head laterally with respect to said tool, whereby to distribute wear uniformly over said tool.

11. A gear finishing machine including in combination, a bed, a table mounted for reciprocating movement on said bed, a rack type tool mounted on said table, said tool having teeth conjugate to the teeth to be produced on the gear to be finished, a head disposed above said tool, means on said head for rotatably mounting a gear to be finished in meshing engagement with said tool, hydraulic means for effecting reciprocation of said table whereby to produce rotation of said gear, hydraulic means for feeding said head downwardly toward said tool, said last mentioned hydraulic means being controlled by said first mentioned hydraulic means.

ERNEST A. OVERSTEDT.
